UNITED STATES PATENT OFFICE.

RAYMOND D. SMITH, OF ARLINGTON, MASSACHUSETTS.

AUTOMATIC CIRCUIT-BREAKER.

1,328,460.

Specification of Letters Patent. Patented Jan. 20, 1920.

Application filed September 7, 1916, Serial No. 118,908. Renewed April 10, 1919. Serial No. 289,135.

To all whom it may concern:

Be it known that I, RAYMOND D. SMITH, a citizen of the United States, residing at Arlington, in the county of Middlesex and

5 State of Massachusetts, have invented certain new and useful Improvements in Automatic Circuit-Breakers, of which the following is a specification.

My invention relates to delayed acting, 10 automatic circuit breakers and specifically to a circuit breaker for use with currents of considerable magnitude wherein relatively heavy movable blades or their equivalents are sometimes used as current carriers, the 15 construction which characterizes this type of circuit breaker usually being such that considerable friction opposes the movement of such blades in breaking the circuit.

The object of my invention is therefore to 20 provide an improved circuit breaker of the above cited type wherein upon suitable actuation of simple, convenient controlling means, (and preferably controlling means of conventional type such as are usually provided for the operation of a blade switch) a tension may be established tending, and sufficient, to cause a desirably quick movement of the blades for breaking the circuit, but wherein such tension is normally 25 opposed in its action to so break the circuit by a thermostatically controlled detent device, operative thermal energization of which (preferably through the agency of a thermally adjustable electric heating unit) is be- 30 gun by the said actuation of the controlling means, and which after a predetermined time interval operates to release the switch blades and cause thereby an automatic and quick break of the circuit.

40 Other and specific objects of my present invention reside in the provision of auxiliary control instrumentalities, preferably associated in construction with the main controlling means above referred to, whereby, 45 at will, the said normally active detent device may be manually rendered inoperative to hold the switch closed, which switch may then be manually operated in the usual manner to make or break the circuit independent 50 of automatic or other features present; in the provision of a thermally insulated, ele- 55 tric heating unit with efficient means for the conduction of heat therefrom to the thermostatic; and further, in the compact and simple arrangement of the various operative

and time adjustive devices whereby their full control may be had manually and selectively through the agency of few and convenient actuating extensions.

The advantages residing in the accomplishments of these objects as shown in the chosen illustrative embodiment of my invention will be apparent to those skilled in the art, and other details and improvements in switch construction will also appear from 65 the description and drawings hereof.

In the drawings:—Figure 1 is a detail view of the thermostatically controlled detent device taken partly in section on the planes 1—1 in Fig. 6; Fig. 2 shows a partial vertical section of the axially expandible, thermostatic disk taken on the axial plane 2—2 in Fig. 6; Fig. 3 is a right, side elevation of the entire circuit breaker showing the casing therefor in section; Fig. 4 is a 70 front elevation of the thermostatically controlled detent device and of the electric heating unit and auxiliary switch therefor, taken partly in section on the vertical plane 4—4 in Fig. 1; Fig. 5 is a front elevation of the 75 circuit breaker with certain detent parts omitted for clearness; Fig. 6 is a complete 80 plan view of the circuit breaker, showing in sectional detail the construction of certain rheostat parts; Fig. 7 is a diagram of elec- 85 trical connections; and Fig. 8, a view taken partly in section on the horizontal planes 8—8 in Fig. 3, shows more clearly and in detail the construction of the auxiliary heating circuit switch with its operative me- 90 chanical connections, and the pivoted construction of the rheostat lever.

Throughout the drawings and in the following description, similar and correspond- 95 ing parts are indicated by the same reference characters.

An insulating support panel usually constructed of slate, is shown at 1, and carries the conventional pole contact clips 2 which are adapted to receive the swinging, conductive blades 3 pivoted each in a correspond- 100 ing pole clip 4 at their opposite ends, the said blades being spaced and braced at their top by a connecting, non-conductive bar 5. Pivoted concentrically with the blades 3 is 105 a swinging, frame 6 carrying a control handle 17 and connected to the blade structure by the two heavy, coiled springs 7, 7. The frame 6 is provided with buffer clips 8, 8, to absorb the shock of contact when the 110

springs act to open the circuit. A compound bellcrank, pivoted detent lever is shown at 9 having a catch formation 10 at one end, normally positioned to engage with 5 a spur projection 11 on the blade structure, and being adjustably and positively engaged in one direction by the downwardly disposed arm 12 which carries at its end a roller 13 maintained in contact with the thermostat 10 disk 14, by the spring 15.

The construction of this thermostat as shown in Fig. 2, comprises two annularly corrugated and expansible diaphragms 16 and 17 joined fluid tight at their periphery 15 and filled with an expansible material sensible to changes in temperature. Reinforcing straps 18 prevent excessive axial expansion of the disk and afford means for conveniently mounting the same in surface contact 20 with an upright, metallic, heat-conducting strip 19.

Although the particular form of thermostat which I have shown for tripping the detent, namely an axially expansible, liquid-filled disk, is not essential to operativeness, and might be replaced by other equally powerful forms of thermostats, it will be appreciated that the heretofore mentioned friction which must necessarily accompany 25 a construction satisfactory for making and breaking large currents, renders necessary a relatively powerful spring means to produce a quick and positive break of the circuit, and that a detent device operative to oppose such 30 spring means must be capable of producing an appreciable amount of movement and of exerting sufficient force to overcome friction at the detent contact surfaces. I have found a disk form of thermostat preëminently satisfactory 35 for use in this connection both as to its power and compactness and also because of the even degree of expansion which between the limits of movement may be made to vary nearly in direct proportion to 40 the change in temperature.

The asbestos layer 20 serves to thermally insulate the heat conducting strip 19 from the surrounding air as well as from the metallic supporting bracket 21. This heat conducting strip as shown best in Fig. 4, extends downwardly and is formed tightly around a horizontal copper tube 22, on which tube, separated therefrom by electrical insulating material, is a winding of resistance 50 wire, designed to heat said tube sufficiently to operatively raise the temperature of the thermostat in the desired time interval. Insulating end supports 35 are provided at the ends of the tube, one carrying the winding 55 terminal binding post 36 and the other, the winding terminal clip 33.

A second, and wholly mechanical detent lever is shown at 23, spring-actuated to engage the swinging frame 6 in the position 60 shown in Fig. 3, and to hold the same against

the tension of the springs 7, 7. As will be evident from the drawings this detent may be disengaged at will by pressure upon the thumb button 24 seated in a socket at the end of the control handle 17.

An auxiliary switch is provided at one end 70 of the resistance unit and is normally positioned to break the circuit therethrough by the coiled spring 26 which spring acts on the plunger 28. As clearly shown in Fig. 3, the 75 plunger is adapted to be actuated by the swinging frame 6 against the action of spring 26 to close the switch and to electrically energize the normally inactive heating unit, as will be clear from the diagram of 80 connections in Fig. 7, where the corresponding symbols bear the same reference characters as the actual structural parts which they represent.

In Fig. 8 a detail of the auxiliary switch 85 is shown wherein the conductive blade 30 is shown pivoted upon, and insulated from, the supporting spindle 31 of the heating spool, and which is provided with an insulated operating extension 32 connected in an obvious manner to the plunger 28. The blade 30 engages with pole clips 33, 34 mounted upon the insulating end support 35 of the heating unit.

As evident from the diagram of connections and as also evident from the structure shown in the drawings, an adjustable rheostat is placed in series with the heating unit, this rheostat comprising a series of insulated spools 37, wound in series with resistance 95 wire, and adapted individually to be put in series with the heating unit circuit to the extent of any selective number, by the rheostat arm 40. This arm is pivoted and provided with electrical connections thereto, as 100 shown at 41 in Fig. 8, and by means of a carried contact spring 42, bearing on the end of each spool in passing, operates in a well known way to vary the resistance and thereby the heat generated by the electric unit, 110 and accordingly the time required to heat the thermostat.

The operation will have been obvious from the foregoing description. Closing the switch constitutes merely the pressure upon the thumb button and swinging of the handle and blades from the full line portion of the former and the broken line portion of the latter in Fig. 3 to the broken line position of the former and the full line position 115 of the latter in the same figure. Causing delayed opening of the switch constitutes merely the movement of the handle, to its position shown in Fig. 3. The blade structure will of course be retained by the detent 9 and the heating unit will be thrown into circuit to release the detent, whereupon the circuit will be automatically broken.

Pivoted to the spur 11, I have shown a rocking lever 44, which is engaged by a col- 120

lar 45, carried upon the release rod 46. This rocking lever as clearly shown in Figs. 3 and 6, upon depression of the thumb button 24 and consequent downward movement of the rod 46, will act to raise the lever 9 and release the blade structure for movement with the frame 6, so that in such manner the switch may be manually opened without operation of delayed opening means.

10 By a simple modification in the electrical connection of the rheostat and electric heating unit it will be apparent to those skilled in the art that the self-opening switch herein illustrated could be adapted for use as a 15 combined motor starting switch and automatic circuit breaker for protecting motors and the like from excessive heating due to continued overload. For such use it will be clear that the heating unit should be so connected in circuit that the current flowing therethrough shall be proportional to the line current. If desired, the three blade structure could be replaced by the usual 20 double or single pole type of swinging contact arm, which arm could be arranged to cut out, by steps, starting resistance when approaching its circuit closing position, and which, upon being tensioned to open the circuit and locked by the thermostatically controlled detent against such tension, would 25 act in an obvious manner to automatically guard against excessive and continued overloads to any predetermined degree.

An advantage resident in such use of my 30 improved self opening switch as a protective circuit breaker is obviously that the circuit will be automatically broken through the agency of heat generated by the current, which heat will be directly proportioned to the heat caused by the excessive current in the motor, regardless of the magnitude of the current which causes such heat. Thus differences in atmospheric temperature are allowed for and are equally 35 effective on the protected device and the automatic means for breaking the circuit, the said means being therefore governed properly in accordance to the heating effect of the current, from which it is desired to 40 protect the motor, rather than by the magnitude of the current as in various common types of electromagnetic protective circuit-breakers.

For use of my improved circuit-breaker 45 as a protective device alone, it will be clear that the control frame 6 may be permanently maintained in its position as shown in Fig. 3, and a control handle provided for actuating the blade structure directly; or 50 that the control frame may be dispensed with and connection of the springs 7, 7, made to some rigid portion of the switch body, the auxiliary switch 30 in this case, being permanently closed.

55 Other applications of my present invention to the requirements of automatic circuit breakers will be obvious to those skilled in the art, and without, therefore, limiting myself to the precise embodiment herein disclosed what I claim as new is:

70

1. An automatic circuit-breaker embodying in combination with means for making and breaking a circuit; a manually operable actuating member arranged to be movable relative to said means and adapted 75 when so moved to energize tensioning means tending to break the circuit; a detent device, with a controlling thermostat therefor, normally arranged and positioned to latch and hold said first means in a position to 80 close the circuit against the opening action of said tensioning means; and a normally inactive heating unit operatively related to the said thermostat and operably related to said member whereby the said thermostat 85 may be thermally energized to cause a release of said means from restraint by said detent device.

2. An automatic circuit-breaker embodying in combination with means therein for 90 making and breaking a circuit; a manually operable actuating member arranged to be movable relative to said means; a resilient connection between said member and said means, arranged to oppose the relative 95 movement thereof; an adjustable detent device positioned normally to latch and hold the said first means in its circuit closing position against movement with said member; a second detent arranged releasably 100 and automatically to lock the said member separated from said means against the action of the said resilient connection; and a thermostat and normally inactive electric 105 heating unit therefor, operatively related to the first detent device to cause a release therefrom of the said first means; together with means governing the said electric heating unit and operably related to the said member, whereby the said heating unit may 110 be operatively energized.

3. An automatic circuit-breaker embodying in combination with means therein for making and breaking a circuit; a separate member concentrically pivoted with said 115 means having a handle extension for the manual actuation thereof; a resilient connection between said member and said means arranged to oppose a relative movement thereof; a detent device positioned 120 normally to latch and hold the said first means in its circuit-closing position against movement with said member; a second detent arranged releasably and automatically to lock the said member separated from said 125 means against the action of the said resilient connection; an operative extension structurally associated with the said handle extension and adapted by similar actuation thereof to release either the said means or 130

the said member from restraint by their said respective detents; and a thermostat and normally inactive electric heating unit therefor, operatively related to the said first 5 detent device to cause a release therefrom of the said first means; and means governing the said electric heating unit and operably related to the said member, whereby the said heating unit may be operatively 10 energized.

4. An automatic circuit-breaker embodying in combination with means therein for making and breaking a circuit; a separate member concentrically pivoted with said 15 means having a handle extension for the manual actuation thereof; a resilient connection between said member and said means arranged to oppose a relative movement thereof; a spring actuated detent device positioned normally to latch and hold the 20 said first means in its circuit-closing position by adjustable engagement therewith; a second spring actuated detent arranged to automatically lock the said member in a 25 tensioned position relative to said means; an operative push rod structurally associated with the said handle extension and adapted by similar depressions thereof to release both the said means and the said 30 member from restraint by their respective detents; and an axially expansible thermostatic disk operatively related to the said first detent device; together with a normally 35 inactive, and structurally separate, electric heating unit and connecting heat conductor therefor, the said heating unit being operably related to said member and to a manually adjustable rheostat, whereby operative energization thereof is secured and 40 controlled.

5. In an automatic circuit breaker including means for making and breaking the circuit and automatic means operatively associated therewith to move the said first 45 means to break the circuit; in combination; a detent device normally operative to engage and hold the said first means against the action of said automatic means; and a 50 thermostatic disk adapted to be increased in axial thickness by the volumetric expansion of a contained fluid, and arranged and positioned in operative relation to the said detent device to move the same when thermally energized, thereby to cause release of the said 55 first means.

6. In an automatic circuit breaker including means for making and breaking the circuit and automatic means operatively associated therewith to move the said first means 60 to break the circuit; in combination; a detent device normally operative to engage and hold the said first means against the action of said automatic means; and an axially 65 expansible thermostatic disk arranged in operative relation to said detent device; to-

gether with an electric heating unit arranged in operative connection to the main circuit and an operative thermal relation to the said thermostat and thereby adapted to energize the same for causing a release of 70 the said first means.

7. In an automatic circuit-breaker including means for making and breaking the circuit and automatic means operatively associated therewith to move the said first means 75 to break the circuit, in combination; a detent device normally operative to engage and hold the said first means against the action of said automatic means; and an axially expansible thermostatic disk arranged in operative relation to said detent device; together with a normally inactive electric heating unit arranged in operative thermal relation to the said thermostat and thereby adapted, when rendered operative, to energize the same for causing a release of the 80 85 said first means.

8. In an automatic circuit-breaker including means for making and breaking the circuit and automatic means operatively associated therewith to move the said first means to break the circuit; in combination; a detent device normally operative to engage and hold the said first means against the action of said automatic means; and an 90 axially expansible thermostatic disk arranged in operative relation to said detent device; together with an electric heating unit comprising a metallic base carrying an insulated resistance winding with a heat 95 conductive connection between said base and said thermostat, whereby operative thermal energization of the thermostat for causing a 100 release of the said first means is secured.

9. In an automatic circuit-breaker including means for making and breaking the circuit and automatic means operatively associated therewith to move the said first means to break the circuit, in combination; a detent 105 normally operative to engage and hold the said first means against the action of said automatic means; and an expansible thermostatic disk with an operatively associated heating unit therefor; together with manually adjustable means, operatively related to 110 the said heating unit and adapted to regulate the operative delivery of heat to the 115 thermostat.

10. In an automatic circuit-breaker including means for making and breaking the circuit and automatic means operatively associated therewith to move the said first means to break the circuit, in combination; a detent device normally operative to engage and hold the said first means against 120 the action of said automatic means; and an axially expansible thermostatic disk with an operatively associated electric heating unit 125 therefor; together with a variable resistance device connected in circuit with the said 130

heater unit and adapted by manual adjustment to regulate the operative delivery of heat to said thermostat.

11. An electric circuit breaker having 5 manually operable means for making and breaking the circuit and embodying in combination with said means; a structurally separate actuating member therefor having a normally tensioned resilient connection to 10 said means adapted to resist movement of the said actuating member relative to said means; a detent device arranged and positioned normally to latch and hold the said means in a position to close the circuit; a 15 second detent arranged and positioned automatically to catch and hold the said actuating member separated from said means against the action of said resilient connection therebetween; and a thermostat adapted 20 upon thermal energization thereof to move the said detent device to release said means thereby to open the circuit; together with an electrically resistive heating unit arranged when energized to heat the thermo- 25 stat, and an auxiliary switch device operably related to the said actuating extension and arranged to control the circuit through said heating unit.

12. An electric circuit breaker having 30 manually operable means for making and breaking the circuit and embodying in combination with said means; a structurally separate actuating member therefor with normally tensioned resilient connection to said 35 means adapted to resist movement of the said actuating member relative to said means; a detent device arranged and positioned normally to latch and hold the said means in a position to close the circuit; a 40 second detent arranged and positioned automatically to catch and hold the said actuating member separated from said means against the action of said resilient connection therebetween; a thermostat adapted 45 upon thermal energization thereof to move the said detent device to release said means and open the circuit; an electrically resistive heating unit arranged when energized to heat the thermostat; and an auxiliary 50 switch device operably related to the said actuating extension and arranged to control the circuit through said heating unit; together with a manually adjustable device operatively associated with the said heat- 55 ing unit whereby the rate of heat delivery to the thermostat may be varied.

13. An electric circuit breaker having 60 manually operable means for making and breaking the circuit and embodying in combination with said means; a structurally separate actuating member therefor with normally tensioned resilient connection to said 65 means adapted to resist movement of the said actuating member relative to said means; a 70 detent device arranged and positioned automatically to latch and hold the said means in a position to close the circuit; a second detent arranged and positioned automatically to catch and hold the said actuating member separated from said means against the action of 75 said resilient connection therebetween; manually operable instrumentalities structurally associated with the said actuating member and arranged upon suitable actuation thereof in one position of the said member to release the said means from the said detent device, and upon similar actuation thereof in another position of said member to release the said member from the said second detent; and a thermostat adapted 80 upon thermal energization thereof to move the said detent device to release said means and open the circuit; together with an electrically resistive heating unit arranged when energized to heat the thermostat, and an auxiliary switch device operably related to the said actuating extension and arranged to control the circuit through said heating unit.

14. An electric circuit breaker having 90 manually operable means for making and breaking the circuit and embodying in combination with said means; a structurally separate actuating member therefor with normally tensioned resilient connection to said 95 means adapted to resist movement of the said actuating member relative to said means; a detent device arranged and positioned normally to latch and hold the said means in a position to close the circuit; a second detent arranged and positioned automatically to catch and hold the said actuating member separated from said means against the action of said resilient connection 100 therebetween; and a disk thermostat adapted 105 by axial expansion upon thermal energization thereof to move the said detent device to release said means and open the circuit; together with an electrically resistive heating unit structurally separate from the thermostat with heat conducting means between said unit and said thermostat, and an auxiliary switch device operably related to the said actuating extension and arranged to 110 control the circuit through said heating unit.

15. In combination with a delayed acting automatic circuit breaker having manually operable, normally deenergized, automatically acting means for breaking the circuit, the said means, including a releasable detent 115 device normally positioned to maintain the circuit closed; a thermostatic disk adapted for thermally caused, axial expansion, operatively related to said detent device to release the latter by said expansion; an electrically and thermally insulated heating unit 120 comprising a tubular, metallic body wound with electrically resistive wire insulated therefrom, and having a metallic, heat-conducting portion extending therefrom and 125 130

- terminating in surface contact with the thermostatic disk, all substantially as shown and described.
16. In combination with a delayed acting, 5 automatic circuit breaker having manually operable, normally deenergized, automatically acting means for breaking the circuit, the said means including a releasable detent device normally positioned to maintain 10 the circuit closed; a thermostat and electrical heating unit therefor arranged when energized to cause the release of said detent device; and a switch device, normally arranged to open the circuit through said electrical unit but operatively related to said 15 manually operable means thereby to be actuated to close the circuit when said automatically acting means are manually energized.
17. An electric switch embodying an oscillatory contact member; an oscillatory actuator element mounted to swing with and positively to impel said member in one direction of its oscillation and further arranged 20 for swinging displacement relative to said member in the opposite direction of oscillation; a spring connection between said element and said member whereby said relative displacement of said element tensions said member for follow-up movement from 25 a circuit making to a circuit breaking position; a detent arranged to prevent said follow-up movement of said member when said element is displaced therefrom; means to hold said member so displaced; and normally inactive, slow acting, instrumentalities arranged to be operatively energized by said displacement of said element, and thereby rendered active to free said member from said detent after a predetermined interval 30 of time.

Signed at Boston, Massachusetts, this sixth day of September, 1916.
